DESIGN FOR A TEXTILE FABRIC OR SIMILAR ARTICLE

Ethel R. Duhan, New York, N. Y., assignor to Holmes & Zucker, Inc., New York, N. Y.

Application March 13, 1945, Serial No. 118,461

Term of patent 7 years

(Cl. D92—1)

To all whom it may concern:

Be it known that I, Ethel R. Duhan, a citizen of the United States, residing in the Borough of Manhattan, city and State of New York, have invented a new, original, and ornamental Design for Textile Fabrics or Similar Articles, of which the following is a specification, reference being had to the accompanying drawing, forming a part thereof.

The figure is a plan view of the textile fabric showing my new design, the repeated unit of which is substantially contained within the dot and dash lines.

I claim:

The ornamental design for a textile fabric or similar article, as shown and described.

ETHEL R. DUHAN.
